STRETCHING CLAMP

Application filed September 5, 1930. Serial No. 479,889.

This invention relates to stretching clamps. While the clamp is particularly adapted for the stretching of leather hides and other material, it is nevertheless to be distinctly understood that the invention is not to be limited to a leather stretching clamp, but is applicable to any use where it is desired to stretch sheet material.

In developing this invention, the stretching of leather will be discussed in detail as one of the many applications of the invention, but as stated, it is not to be understood in any sense as limiting the invention to the stretching of leather.

15. In stretching leather it is the usual practice to take the leather after tanning and while it is wet and stretch it. In the usual practice it is frequently the case that the leather is stretched and tacked on frames, or 20. else the leather is engaged by clamps which are gripped in the hand of the operator and pulled outwardly and thereafter hooked into a perforated frame. It will be readily seen that the stretching is an uncertain quantity, 25. depending greatly upon the skill of the operator, and also it is apparent that the maximum stretching cannot be determined by this method. Further, it frequently happens that when the operator's hand slips from 30. any cause whatsoever, that his hand is in contact with the perforated metal frame or the means to which it is desired to attach the clamp. The consequence of this is that the operator's hand is cut or injured by 35. scraping it across the frame. In addition to this defect, the operator's hand is in an awkward position and projects below the clamp, thus greatly hindering him in attaching the clamp in place.

40. Further than this, it is apparent that with this uncertain method of stretching, that the grain is frequently injured as an attempt to place considerable tension upon the leather, frequently results in either too much tension 45. or too little tension, thereby altering the appearance of the grain and spoiling the leather or hide for certain uses.

This invention is designed to overcome the defects noted above, and the objects of 50. this invention are to provide a clamp which

not only grips the leather, but also stretches the leather a predetermined amount. The clamp in actual practice secures an additional stretching of the leather which has not heretofore been possible. When it is considered that a slight increase all the way around a "side" or hide results in a material increase in the area of the leather or hide, and when it is appreciated that the leather is sold by the square foot, it is at 60 once apparent that even a small gain completely around the "side" or hide will result in a material increase in the number of square feet available for sale. This invention accomplishes the above outlined objects 65 without injuring the leather in any way, as it secures an additional and predetermined amount of stretching.

Further objects of this invention are to provide a stretching clamp which protects 70 the hand of the operator, and which permits the hand of the operator to be at all times during the stretching operation, positioned above the body portion of the apparatus, that is to say, with the body portion 75 of the apparatus located between the perforated frame or the support to which the device is attached, and the hand of the operator so that he does not have to hold his hand in an awkward position during the 80 stretching or during the actual attaching of the device to the perforated sheet metal support.

A further object of this invention is to provide a stretching clamp which allows the 85 leather to be stretched to the desired extent by the operator and which thereafter provides a pre-determined amount of additional stretching which cannot be exceeded and which does not damage the grain of the 90 leather, but which protects the grain of the leather, as this pre-determined amount of stretching is uniformly applied throughout the entire "side" or hide.

Further objects are to provide a stretching clamp which is of very simple construction, which has no fragile or easily damaged parts, which is cheap to make, which may be formed from stampings if desired, and which is easy to operate.

In certain forms of the invention, a further object is to provide a stretching clamp having the characteristics above noted, which automatically opens and closes the clamping jaw when the main lever or member is manipulated so that only one operation is required of the operator instead of two. That is to say, the manipulation of the main member not only stretches the leather a pre-determined amount, but also controls the gripping of the leather by the clamp, thereby securing this double function.

It is to be distinctly understood that the term "leather" is used in this description and in the appended claims to designate any sheet material which it is desired to stretch and is merely used to avoid needless repetition.

20 Embodiments of the invention are shown in the accompanying drawings in which:—

Fig. 1 is a longitudinal sectional view of a leather-stretching device embodying my invention, the device being shown applied to 25 a portion of a leather-supporting frame; Fig. 2, a similar sectional view showing the improved device after the clamp which engages the leather has been shifted or telescoped within the mounting which is hooked 30 onto the leather-supporting frame; Fig. 3, a plan view of the improved device, the stretched leather being shown brokenly; Fig. 4, a longitudinal sectional view showing 35 a modification of the invention; and Fig. 5, a longitudinal section showing another modification.

Referring to the drawings, it will be seen that the usual supporting means has been 40 shown as a frame (1) provided with perforated metal strips (2) carried thereby.

The clamp comprises a body portion (3), which is formed of sheet metal and is channel shaped, although obviously other shapes could be employed. The channel shaped 45 body portion, however, is preferred as it permits the use of the body portion as a guide for a slide (4), also formed of sheet metal. The slide (4) is a movable member, as will be seen from Figures 1, 2 and 3, and 50 is adapted to slide inwardly or outwardly within the channel shaped body portion. It is operated by means of a toggle link mechanism consisting of a sheet metal channel shaped manipulating lever (5), which is 55 pivoted, as indicated at (6), within the body portion. This lever is provided with a looped grip (7), so that the operator's finger may be inserted therein if so desired. However, in the initial operation, the lever projects 60 vertically upwardly, as shown in Figure 1, and the hand of the operator grasps around the upwardly projecting lever.

The lever (5) is connected to the slide by means of one or more links (8) as shown. 65 The pivots (6) do not extend completely

across the body portion, as may be seen from Figure 3, and thus permit the rocking of the lever (5) downwardly, as will herein-after be described, into a position to carry the rear pivot point (9) of the links (8) past dead center, as shown in Figure 2, to thus lock the slide (4) in its retracted position.

The forward ends of the links (8) are pivoted, as indicated at (10) to the slide (4). 75 It is preferable to turn a pair of ears (11) over from the body portion (3) so as to effectively hold the slide (4) against upward motion.

The slide (4) is provided with any sort 80 of clamp adapted to engage the leather or other sheet material (12). For example, the slide may be provided with an upturned lip (13) which cooperates with a down-turned lip or recessed member (14) of an upper clamping jaw (15), the slide forming the lower clamping jaw. This upper clamping jaw (15) is operated by means of a small hand lever (16). It is to be distinctly understood at this point that other 90 types of clamps may be employed.

It is also preferable to form the body portion (3) with a downwardly and forwardly projecting hook (17), which is adapted to enter any one of the apertures 95 (18) in the support, as shown in Figures 1 and 2.

In operating the device, the lever (5) is moved to a vertical position, as shown in Figure 1, and the edge of the leather (12) is gripped, as indicated in such figure. Thereafter, the operator grasps the upwardly projecting lever and draws the entire mechanism backwardly and hooks the hook (17) through the appropriate aperture (18) in the support. During this operation the operator's hand is fully protected, even if the clamp should slip, as the body portion of the stretching clamp is between his hand and the support, and consequently no tearing of the operator's hand can result as was frequently heretofore the case.

After the stretching clamp has been locked to the support, the operator gives the leather an additional predetermined stretch by rocking the lever (5) downwardly, thereby drawing the leather rearwardly a fixed and predetermined amount.

In actual practice it has been found that this predetermined additional stretch given the leather does not injure the grain and materially increases the total area of the leather. In view of the fact that the leather is sold by the square foot, it is apparent that an additional saving is secured by this apparatus.

It is to be noted particularly that no judgment is required of the operator in securing this additional stretch, as the ad-

ditional stretch is pre-determined and cannot be exceeded even by a careless operator. Further, it will be noted that the operator's hand is fully protected at all times and there is no danger of cutting or tearing his hand when this apparatus is used.

In the extensible stretching-device, or unit, described, the body 3 constitutes a hook-equipped mounting; the slide 4 and parts carried thereby constitute a bodily-shiftable clamp having forwardly presented gripper-jaws; and the lever 7 and links 8 constitute a manually operated clamp-retracting device by means of which rearward shifting of the clamp may be effected after the clamp has gripped the leather and the mounting, or base-frame, 3 has been hooked onto the foraminous member 2 of the leather-supporting frame 1.

20 In effect, the clamp is adapted to be telescoped within the mounting in the collapsed condition of the leather-stretching device.

It may be remarked that while the improved leather-stretching device is in the extended condition, it may be manipulated to apply to the leather an initial hand-pull which may be of such intensity as the particular portion of the leather may require, and, thereafter, a lever-pull of pre-determined amplitude. Consequently, a greater stretch than has heretofore been possible with a device of this general type may be safely applied to the leather, at such points as require it. Also, ease of release is an important feature of the improved device, since the lever may be thrown over to relieve the pull prior to disengaging the hook from the leather-supporting frame.

Referring to Figure 4, it will be seen that the same idea is carried out in this form of the invention. In this form of the invention, a body portion (19) is provided which is constructed in a manner quite similar to that previously described. It carries the slide (20), which is equipped with an upturned lip or jaw (21).

The slide (20) is connected to the lever (22) by one or more links (23) as shown.

The movable jaw (24) is formed integrally with the member (25), which is loosely pivoted to the slide (20). The member (25) is provided with an upwardly pressed recessed portion (26) which houses a small compression spring (27). The upwardly pressed portion (26) engages a cam surface formed integrally with the body portion (19). This cam consists of an upturned portion (27) and a horizontal or flat portion (28).

60 When the lever (22) is rocked into its dotted line position, as shown in Figure 4, the movable jaw is raised upwardly, as shown in dotted line, due to the sliding of the upward projection (26) upon the portion (27) of the cam. This automatically

opens the clamp and permits the insertion of the edge of the leather. When the lever (22) is initially moved rearwardly to its full line position, the projection (26) slides downwardly beneath the horizontal portion (28) of the cam, and thus automatically closes the jaws. Thereafter the operator gripping the upwardly projecting lever (22) draws the body portion rearwardly and hooks the hook (29) into the support, as previously described. Thereafter he rocks the lever (22) downwardly, and thus provides the additional stretch of a pre-determined amount for the leather.

In this form of the invention it will be seen that automatical means are provided for opening and closing the gripping clamp, and also this means is utilized to draw the slide rearwardly within the body portion.

It is to be distinctly understood that other means may be employed for automatically opening and closing the clamping jaws. For example, as shown in Figure 5, link work can be employed. In this form of the invention the body portion (30) carries the slide (31) in the same manner as that previously described. The slide is provided with an upturned lip (32), which cooperates with the downturned lip (33) of the upper clamping jaw (34). A small lever (35) opens and closes the jaws as it is rocked about its pivot point (36). The lever (35) is urged into the position shown in Figure 5 by means of a spring (37). However, it is adapted to be rocked in the contrary direction, that is in a counter-clockwise direction as viewed in Figure 5, by means of the link (38) pivoted to the slide operating link (39).

It is to be noted that the slide operating link (39) is provided with a slot (40) within which the forward pin (41) and connecting link to the slide is located. The link (38) is also slotted, as indicated at (42).

In the position of the parts shown in Figure 5 the jaws are just about to be released. The operating lever (not shown) is in its vertical position, as has been shown in full lines in Figure 4. A slight additional forward rocking of this operating lever causes the link (39) to move forwardly and to force the connected link (38) forwardly, thus engaging the pin (43) carried at the upper end of the locking lever (35). This rocks the lever (35) in a counter-clockwise direction, and raises the upper jaw as the lever (35) engages beneath the tongue (44) of the member (34).

Obviously when the main or operating lever is initially rocked a slight distance rearwardly, the jaws are again closed through the action of the spring (37) and the locking lever (35). Further, motion of the main lever retracts the slide (31) and provides the additional stretch heretofore described.

It is to be distinctly understood that the means for automatically opening and closing the jaws may be varied, and that the particular forms chosen for illustration are merely illustrative of the general principle.

Any suitable means may be employed for limiting the forward motion of the slides in the different forms of the invention. For example, in Figure 5 the slide (31) is provided with shoulders (45) which engage the inturned lips (46) of the body portion (30).

In the form shown in Figures 1 and 4, the links (8) and (23) may respectively contact with the portions (11) and (28). Also in these two forms, the bottom forward corner of the lever (5) or (22) respectively may engage the bottom of the body portion, and may thus limit the forward motion of the slide.

20 It will be seen that a novel form of stretching clamp has been provided which is of extremely simple construction, which is eminently practical, which is reliable in operation, and which is very easy to operate.

25 It will be seen further that the novel form of stretching clamp provides a pre-determined additional stretch, protects the hand of the operator, and does not destroy or in any way injure the grain of the leather.

30 It will be seen further that the device may be formed of sheet metal stampings if so desired, and that it may be made with the utmost cheapness.

Although the invention has been described in considerable detail, it is to be understood that such description is intended as illustrative rather than limiting, and the appended claims are to be construed as broadly as permissible, in view of the prior art.

40 I claim:

1. An extensible stretching-device unit of the character set forth, comprising: a mounting equipped with means for engaging a support; a bodily-shiftable clamp on said mounting, having a forwardly presented pair of gripper-jaws; and manual actuating means connecting said mounting and clamp, operative to extend and collapse said stretching-device.

50 2. A device as specified in claim 1, in which the rear end of said mounting has its lower side equipped with a hook adapted to engage said support.

55 3. A device as specified in claim 1, in which said actuating means is equipped with a finger-piece adapted to be thrown rearwardly in the operation of shifting said clamp with relation to said mounting.

60 4. A device as specified in claim 1, in which said clamp is slidable within said mounting and has its gripper-jaws projected some distance in advance of the forward end of the mounting when the device is in extended condition.

65 5. A device as specified in claim 1, in

which said actuating means comprises a hand-lever having pivotal connection with said mounting and having link-connection with the body-portion of said clamp.

6. A device as specified in claim 1, in which said actuating means comprises a hand-lever equipped with a finger-piece and arms pivotally connected near their free ends with side walls with which said mounting is provided, and comprises, also, links disposed between the planes of said arms and pivotally connected at one end with said arms and at the other end with the body-portion of said clamp.

7. A device as specified in claim 1, in which said mounting comprises a member of U-shaped cross-section having an open front end and the bottom wall of said mounting is equipped with a depending forwardly extending hook; and in which said actuating means comprises a lever pivotally connected with the side walls of said mounting and links connecting said lever with the side walls of the body of said clamp.

8. A device as specified in claim 1, in which said mounting comprises a member of U-shape cross-section having an open front end and the bottom wall of said mounting is equipped with a depending forwardly extending hook; in which said actuating means comprises a lever pivotally connected with the side walls of said mounting and links connecting said lever with the side walls of the body of said clamp; and in which one of said gripper-jaws is a movable lever-actuated member.

9. An extensible stretching-device unit of the character set forth, comprising: a mounting equipped with means for engaging a support; a bodily-shiftable clamp slidably carried by said mounting having a forwardly presented pair of gripper-jaws, one of which is movable; actuating means connecting said mounting and clamp, operative to extend and collapse said stretching-device; and means for automatically actuating the movable gripper-jaw during the operation of shifting said clamp on said mounting.

10. An extensible stretching-device unit of the character set forth, comprising: a mounting equipped with means for engaging a support; a bodily-shiftable clamp on said mounting having a forwardly presented pair of gripper jaws; and actuating means for effecting shifting of said clamp with relation to said mounting.

In testimony whereof, the signature of the inventor is affixed hereto.

WALTER E. DE LAND.
